[57] CLAIM

The ornamental design for a face shield, as shown and described.

DESCRIPTION

FIG. 1 is a front perspective view of a face shield showing my new design;

FIG. 2 is a front elevational view thereof;

FIG. 3 is a right side elevational view thereof, the left side being a mirror image;

FIG. 4 is a rear elevational view thereof;

FIG. 5 is a top plan view thereof; and,

FIG. 6 is a bottom plan view thereof.

The strap shown broken away in FIGS. 1 and 3-6 is understood to represent indeterminate length.
